UNITED STATES PATENT OFFICE.

JULIUS R. WEMLINGER, OF BROOKLYN, NEW YORK.

SHEET PILING.

Application filed January 29, 1927. Serial No. 164,504.

This invention relates to sheet piling of the interlocking type and, specifically, consists of sheet piling composed of identical trough-shaped elements, the longitudinal edges of which are so shaped that the elements can be interlocked and separated laterally, instead of being threaded together longitudinally as usual, and that the elements can be alternately reversed to face in opposite directions, if desired.

This new form of sheet piling, usually made of rolled steel sections, possesses several material advantages not found in prior forms of interlocking sheet piling, as far as I am aware. These advantages are due to the following features of its construction: 1, the trough shape of the elements, which gives the greatest rigidity possible for a given amount of metal; 2, the peculiar shape of the interlocking edges, which permits the lateral engagement and separation of the elements, and also the reversal of alternate elements; 3, the shape of the interlocking edge having the socket for the reception of the T head edge of the adjoining element, whereby the projecting lip, which has to be bent inwardly subsequently to the rolling of the section, can be made much shorter than heretofore, which facilitates the rolling operation and the bending operation and renders said lip much less likely to be distorted by hard material in the driving of the pile.

I am aware that sheet piling capable of being interlocked laterally has heretofore been proposed, but in no instance of which I am aware, can alternate sections be reversed in position and still be laterally interlocked and separated. The alternately reversed position of the elements is very desirable because it imparts the greatest possible stiffness and strength to the piling wall.

The invention is illustrated in the accompanying drawing, in which Fig. 1 is a cross-sectional view of a piling wall composed of the improved elements arranged in reversed position; Fig. 2 is a partial elevation of the same and Fig. 3 is a cross section like Fig. 1 but with the elements not reversed.

In these views, the piling wall is composed of identical trough-shaped elements or sections 1, each of which is flanged along its longitudinal edges, one flange carrying the male T head 2 and the other the female

socket head 3. These sections are rolled to finished shape, with the exception of the lip 4, which is subsequently bent over, as shown, to complete the socket and retain the T head of the adjoining section while permitting its being laterally engaged and disengaged. Said lip is relatively short, so that it can be formed in the rolling operation without the necessity of a deep groove in the rolls. The T and socket heads are so formed, as will be apparent from the drawing, that all the sections may lie on the same side of the vertical plane passing through the interlocking edges, or that alternate sections may lie on opposite sides of said plane, as shown in Fig. 1. As before stated, the alternate arrangement is preferable, on account of the great rigidity thereby obtained but, where the available space is insufficient for the reversed arrangement, the sections may be interlocked in the same relative position, as shown in Fig. 3.

Piling thus constructed is, to a certain degree, flexible, the interlocking edges permitting some angularity between the sections. It is economical to manufacture, easy to install and disassemble, and gives the greatest possible rigidity for the weight of metal used.

Having thus described my invention, what I claim is:

1. A retaining wall of sheet piling, comprising a plurality of identical trough-shaped rolled sections, each section having a rounded T head on one edge and an open mouth socket on the other edge, whereby the sections can be engaged laterally and the front and back depth of the wall can be doubled by reversing alternate sections.

2. A sheet piling unit consisting of a channel section flanged on its edges, one of said flanges carrying a head of rounded T shape and the other flange carrying a projecting claw and an extended lip, the latter being bent over to form, with said claw, a socket in which the T head of an adjacent section can be engaged by lateral entrance, whether said adjacent section is in the same relative position as the first section or is reversed relatively to the same.

In testimony whereof I have hereunto set my hand.

JULIUS R. WEMLINGER.
